ATTY.

UNITED STATES PATENT OFFICE.

LEROY J. MARTEL, OF PAWTUCKET, RHODE ISLAND.

MUFFLER FOR INTERNAL-COMBUSTION ENGINES.

Application filed August 12, 1921. Serial No. 491,860.

To all whom it may concern:

Be it known that I, LEROY J. MARTEL, a citizen of the United States, residing at 87 Boyce Avenue, in the city of Pawtucket, 5 in the county of Providence and State of Rhode Island, have invented certain new and useful Improvements in Mufflers for Internal-Combustion Engines, of which the following is a specification.

10 My invention relates to improvements in mufflers for internal combustion engines, and the purpose of my invention is to provide a device, simple in structure, of comparatively inexpensive construction, and 15 which will reduce to a minimum the sound caused by the explosions of a motor of the type mentioned, and at the same time create little or no back pressure.

These objects are accomplished by the 20 mechanism disclosed by the accompanying drawings, in which—

Figure 1 is a vertical section of my device upon the line C—C of Figures 2 and 3.

Figure 2 is a cross section upon the line 25 a—a of Figure 1, and

Figure 3 is a cross section of my muffler upon the line b—b of Figure 1.

The same parts are designated by the 30 same characters throughout the various views.

In Figure 1, 1 is a cylinder, preferably of metal, provided with heads 10—10 at each end, riveted to the cylinder walls by the rivets 7—7, etc. These heads are annular in shape and have secured to them 35 the funnel shaped members 2—3, the member 2 forming the exhaust for the gases, and the member 3 forming the inlet to the muffler from the engine. These members 2—3 are also secured to the heads 10—10 by 40 the rivets 7—7 or other suitable means. A portion of both members 2 and 3, as is shown, projects beyond and outside the muffler head, as shown in the drawing, and 45 each member terminates within the muffler in the funnel shaped portion 13—14.

At the inlet end of the muffler, and a short distance from the funnel shaped portion 14 of the member 3, and lying partly 50 within the same, is a conical baffle plate or spreader 4, supported by the perforated diaphragm 12 by rivets or other suitable means. The distance between the conical baffle plate

4 and the funnel shaped portion 14 is determined by experiment, but is such as to 55 provide for the easy escape of the gases without creating back pressure.

In addition to the diaphragm 12, there is a like diaphragm 15 located near the exhaust end of the muffler. This second diaphragm 15 is supported by being riveted to the outer wall of the muffler as shown, and a hollow tube 5 extends between the diaphragms 12 and 15 to strengthen and stiffen the entire construction. The diaphragms 12—15 are perforated with a plurality of holes 6—6, as shown best in Figure 2. The escaping gas from the engine entering by the inlet 3 is expanded by the conical member 4, finds its way through the holes 6 into the body of the muffler, and thence makes its exit through like holes 11 in the diaphragm 15 into the space between this diaphragm and the exhaust member 2, and the funnel shaped portion 13 permits 70 of easy egress of the exhaust gas. The number of holes in the diaphragms 12—15 is immaterial, but should be sufficient in number and size to fully take care of the volume of exhaust gas coming from the 75 engine.

It is evident that instead of the funnel shaped interior ends of the inlet and outlet, hollow hemispherical ends may be used without departing from the principle of 80 my invention.

In like manner the number of diaphragms may be varied from one to three, or more, but satisfactory results are obtained with 90 two, as shown.

Having now described my invention what I claim and desire to secure by Letters Patent is:—

In a muffler, a cylindrical body portion, annular heads, each having an outwardly projecting annular flange riveted to opposite ends of said body portion, funnel-shaped inlet and outlet members riveted to opposite heads with their larger ends positioned within said body portion, spaced 95 annular diaphragms having flanged outer edges positioned within said body portion and riveted thereto, a tubular member centrally connecting said diaphragms, said diaphragms having annularly arranged apertures positioned concentrically with said 100 105

tubular member and outwardly of the same, and a conically-shaped spreader having radial ears riveted to one of said diaphragms and extending into the funnel-shaped inlet for the purpose of directing the inflowing gases outwardly toward the apertures in one diaphragm.

In testimony whereof I affix my signature in presence of two witnesses.

LEROY J. MARTEL.
